MICHIGAN.

UNIVERSAL SUPPORT.

Application filed September 4, 1920. Serial No. 408,199.

To all whom it may concern:

Be it known that we, ALFRED COPONY and FERDINAND ZIGANEK, respectively a citizen of the Austrian Republic, and a subject of the King of Roumania, residents, respectively, of Mount Clemens, in the county of Macomb and State of Michigan, and of Detroit, in the county of Wayne and State of Michigan, have invented a new and useful Universal Support, of which the following is a specification:

This invention relates to improvements in universal supports which provide suitable means for efficiently supporting holding or clamping devices for machine tools or vises, and the aim of our improvement is, first, to hold an object in any desired position in relation to any tool with perfect security and, second, to produce such improvement in such a form that it can be manufactured at a price within the reach of the majority of possible users.

Other objects will appear in the course of the following description.

Our invention is illustrated in the accompanying drawing, wherein Fig. 1. is a vertical section through the universal support showing its use in connection with a vise on a work bench. Fig. 2. is a section along line A—A of Fig. 1. Fig. 3. is a top view of Fig. 1. with locking bolt, vise and top plate removed. Fig. 4. is a view in direction B of Fig. 1. and illustrates the locking lever and eccentric of the device only.

Similar reference characters refer to like parts throughout the several views.

Referring to this drawing, 4 represents a vise with a flat base as is ordinarily used in machine shops for bench work. This vise is secured by means of set screws to a top plate 3 which is provided at its lower end with a spherical recess, open at its lowermost point and extending downwardly well below the center of the sphere. A centering hole 12 at the center of the top plate and an auxiliary hole 13 are provided in the top plate. This top plate 3 rests on a plurality of spherical sector pieces 2 made of steel or any other substantial but flexible material by pressing. They are hollow, open on their inner side, flanged on those sides that are in a plane radial to the main vertical axis of the sphere and their outer spherical surface is in close fitting but slidable contact with

the inner spherical surface of top plate 3. 55 The uppermost portion of the flanges of these sector pieces 2 are recessed to provide a seating surface for a locking bolt 7 while the lowermost outside portion of these sector pieces 2 are bent inwardly, upwardly and then downwardly in a semi-circular shape, while the flanged sides of these sector pieces are cut out at the lower end in such a manner that they fit in close contact over such lower outside recessed portion of the sector 60 pieces, thereby effectively reinforcing them.

These sector pieces rest on an annular base 1 which engages said lower recesses of the sector pieces 2. This base 1 is further provided with a central boss 19, bored to receive 70 a locking bolt 7 and can be fastened to the bench top 5 by means of bolts and nuts 6. It is therefore obvious that sector pieces 2 forming a flexible sphere, can be rotated simultaneously on base plate 1 while top plate 75 3 can be rotated and tilted in any direction on sector pieces 2.

Locking bolt 7 has a flat head 20 fitting into the uppermost recesses of sector pieces 2 and is provided at its top central portion 80 with a seat 11 which will engage snugly with a pivot center hole 12 when moved in an upward direction. A cotterpin 10, washers 9 and a partially compressed coil spring 8 provide means for engaging locking bolt 7 with the inside lower portion of the sector pieces 2 thereby giving the locking bolt 7 a constant upward pull. The lower end of this locking bolt 7 engages a pivot nut 14 straddled by a stirrup eccentric 15 which is 90 tied against spreading by means of stay bolt 16. The active outside eccentric surface of the stirrup is symmetrical in relation to its long axis bisecting handle 18 and stay bolt 16, and is made up of two curves compassing the active working surface of the eccentric, the first curve providing for a relatively long downward stroke of bolt when handle 18 is shifted from a position almost horizontal to one nearly 30 degrees from the horizontal while the second portion of the eccentric working curve provides for an additional, relatively short downward stroke of bolt when handle 18 is shifted from a position nearly 30 degrees from the horizontal to an almost vertical position. This gives a comparatively long disengaging stroke with limited power on top of an additional 95 100 105

short compression stroke with relatively high power. Handle 18 engages stirrup eccentric 15 by means of a hole in the central portion of the stirrup and further by means of a nut 17 which is securely seated in rectangular openings in the sides of the stirrup eccentric. This stirrup works against the lowermost flat surface of boss 19.

In operation the universal support will work as follows:

If the universal support should be used as swivel support, to permit the vise being turned in a horizontal plane only, eccentric lever 18 is pulled up to an almost horizontal position thereby permitting the locking bolt 7 to move to its uppermost position bringing teat 11 into engagement with centering hole 12 of the top plate by slightly swiveling the latter. It then is possible to revolve the vise on the sphere using teat 11 as a center and thereby keeping the vise in a horizontal plane. By pushing handle 18 into a position almost vertical from the almost horizontal position teat 11 becomes disengaged from the centering hole 12, spring 8 will be compressed and as soon as disengagement is complete the flat head of the locking bolt 7 will press down on ribs of sector pieces 2 and as all the sector pieces are flexible they will expand the sphere, of which they are component parts, in its largest horizontal diameter and thereby lock the top plate to the base. It is obvious, that on deflection of the sector pieces their outside spherical surface will be in intimate and locking contact with the inside spherical surface of the top plate. The comparatively largest deflection of the sphere will not exceed 1/100 part of an inch after reasonable wear.

Should the vise be set in any position at an angle inclined to the horizontal, locking will take place in an exactly similar manner.

In case this universal base should be used for assembling work where it is necessary to hold the object to be assembled in different predetermined positions tilted towards the horizontal plane, auxiliary stop holes 13 come into play, which engage teat 11 of locking bolt 7 in a similar manner as shown with pivot center hole 12.

Many other changes in the details of construction may be made by those skilled in the art without departing from the spirit of our invention. For instance, the supporting sphere could be made of two pressed half spheres vertically slotted to increase the flexibility and still be efficient as long as the deflecting means are maintained. Two of these universal supports may be used in combination in order to produce a swinging arc in any direction with double the compass of swing possessed by one universal support.

Having set forth our invention, we claim:

1. In a universal support, the combination of a top plate with an internal spherical recess, a spherical, laterally expandable, vertically compressible, deformable base, a base plate to support said deformable base and means for deforming said spherical base to lockably engage by friction the interior spherical recess of said top plate.

2. In a universal support, the combination of an integral top plate, with a spherical recess, adapted to slidably and tiltably engage a spherical base, a spherical, laterally expandable, vertically compressible, deformable base, a base plate to support and rotatably mount said deformable base, to lockably engage by friction the interior spherical recess of said top plate.

3. In a universal support, the combination of an integral top plate, with a spherical recess, the lower edge of which extends below the largest horizontal diameter of a spherical base, adapted to slidably and tiltably engage said spherical base but normally non-removable therefrom, a laterally expandable, vertically compressible, deformable spherical base above referred to, a base plate with an annular bearing surface to rotatably engage said spherical base, means to fasten said base plate to a table, and means for deforming said spherical base to lockably engage by friction the interior spherical recess of said top plate.

4. In a universal support, the combination of a top plate with an internal spherical recess, to rotatably and tiltably engage a spherical deformable base, means for lockably and rotatably engaging the walls of said recess of said top plate with the head of a locking bolt, a spherical, vertically compressible, laterally expandable deformable base above referred to, a base plate adapted to support and rotatably engage said spherical deformable base, said locking bolt to deform said spherical deformable base and means for rotatably engaging said locking bolt with the walls of said recess of said top plate, when the spherical deformable base is non-deformed.

5. In a universal support, the combination of a top plate with an internal spherical recess to rotatably and tiltably engage a spherical deformable base, a spherical deformable, laterally expandable, vertically compressible base above referred to, a base plate to support said spherical base, a boss on said base plate to provide a non-resilient support for means to deform said spherical deformable base, and means to deform said base, to lockably engage by friction the spherical recess of said top plate.

6. In a universal support, the combination of a top plate with a hollow spherical recess to rotatably and tiltably engage a spher-

ical deformable base, said spherical deformable base, a base plate with an annular bearing surface to rotatably engage said spherical deformable base, a locking bolt

bolt a comparative fast disengaging motion from the pivot position with the top plate and a relatively slow locking motion 35 when deforming said ball.

5 to deform said spherical deformable base and means for non-resiliently connecting said locking bolt with said base-plate in a locked position.

9. In a universal support, the combination

10 of a top plate with a hollow spherical recess to rotatably and tiltably engage a spherical deformable base, there being holes in the walls of said spherical recess to engage a locking bolt, a spherical deformable

35 base above referred to, a base plate adapted 40

15 to engage said spherical deformable base, a locking bolt to deform said spherical deformable base, means for rotatably engaging said locking bolt with holes in the 45

20 spherical recess of said top plate and means for connecting said locking bolt with said base plate in a locked position.

50

8. In a universal support, the combination 55 of a top plate having an internal socket fitting a deformable ball rotatable and tilt-able thereon, a deformable ball above referred to, a base plate adapted to engage said deformable ball and provided with an integral boss, a locking bolt to deform said

30 deformable ball, an eccentric with double locking curves working on the said integral boss of said base plate to give said locking
